CENTRIFUGAL FAN

Application filed February 3, 1930. Serial No. 425,433.

The present invention relates to centrifugal fans.

The object of the present invention is to provide a simple and easily operated centrifugal fan, the output of which may be efficiently controlled independently of the speed.

In my copending application, Serial No. 210,666, filed August 4, 1927, I have disclosed a method and apparatus whereby the output of a centrifugal fan may be controlled without the necessity of employing the common but expensive method of speed control or the inefficient method of throttling. Briefly, the principle of the invention of said application consists in output regulation by imparting to the entering fluid a variable and controllable spin velocity in the direction of rotation of the rotor. The specific construction of the prior invention includes a plurality of simultaneously adjustable vanes to direct the entering fluid into the rotor at a variable angle.

The present invention, while operating on the principle of varying output by control of spin velocity, consists of a modification of the prior invention, principally with a view toward economy and simplicity of construction.

In its simplest form, it comprises an inlet chamber which by its shape has an inherent tendency to introduce a spin into the fluid, together with deflecting means adjacent the entrance opening of the chamber, thereby to control the direction of the entering currents of fluid and thus to vary the spin component of velocity. Such deflecting means does not constitute a throttling means because although the air passage may be reduced in cross-sectional area, the volume of fluid passing is itself so far reduced by the limitation of the output of the fan, due to increased spin of the air, that the objectionable features of throttling are entirely avoided.

In the accompanying drawing illustrating what is now considered the preferred form of the invention, Fig. 1 is a side elevation of an induced draft fan with the output controlling means in position for maximum output; Fig. 2 is an end elevation of the fan shown in Fig. 1; and Fig. 3 is a view similar to Fig. 1 show-

ing the output controlling means in position for reduced output.

The illustrated embodiment of the invention comprises a fan having a rotor 4, inlet boxes 6 and 8 on opposite sides of the rotor and an outlet box or scroll 10. The inlet boxes 6 and 8 being of identical construction, a description of one only will suffice. The upper part of the inlet box 6 is of the usual scroll formation, as indicated at 11. The scroll is provided with an eccentric eye 12 which leads directly to the rotor. The inlet box is formed at its lower end with an entrance chamber 14 of peculiar construction. As shown in Fig. 1, the two ends walls of the entrance chamber are designated at 16 and 18. The wall 16, which may be termed a fluid directing wall, instead of forming a straight duct, as in the usual induced draft fan, is curved away from the eye for a short distance. The wall 18 is of circular contour having its center directly below the axis of the rotor and curving in the same general direction as wall 16, but more sharply. The walls 16 and 18 meet the scroll portion of the inlet box in a constricted throat 20.

In order to control and vary the magnitude of the spin velocity of the fluid admitted to the rotor, the entrance chamber 14 is provided with a pivoted gate or deflector 22 which is in the shape of a sector having a curved plate 24 conforming to the inside of the wall 18 and also provided with a reversed lip 26 which conforms to the throat portion of the inlet box when the gate is completely open as shown in Fig. 1. The deflector is also formed with side plates 28 which are secured to a rock shaft 29. The deflector is counter-balanced by a weight 30 and is adapted to be moved to any desired position by a link 32 attached to the rock shaft. By means of the lever 32, the deflector may be moved from full open position, as shown in Fig. 1, through an intermediate position, as shown in Fig. 3, to fully closed position wherein the lip 26 engages with the wall 16 of the entrance chamber.

By variation of the position of the deflector 18, the magnitude of the spin velocity of the fluid entering the rotor may be conveniently

adjusted. When the deflector is in the position shown in Fig. 1, the air enters the inlet chamber in the general direction indicated by the arrows (the rotor turning in a clockwise direction). Because of the spiral contour of the inlet scroll and the curvature of the walls of the entrance chamber, the air tends to circulate somewhat around the inside wall of the scroll before entering the eye. The amount of rotation which the fluid thus assumes in this position of the deflector is, however, too small to cause any serious reduction in fan capacity. In fact, this slight rotation is advantageous in that it causes the fluid to distribute itself uniformly around the eye of the fan. At the open position of the deflector, therefore, the fluid enters the eye along nearly radial lines, and with minimum spin, so that maximum output is obtained.

When the deflector is adjusted, say to the position of Fig. 3, the entering fluid follows the general direction of the arrows and being initially confined to the space immediately adjacent to the outside wall of the scroll, tends to circulate more completely around the casing and to assume a much greater angle of entrance into the eye of the fan. In fact, the fluid may spin more than one complete revolution around the casing before passing into the fan. In other words, the fluid, instead of passing into the eye of the fan along nearly radial lines, now assumes a direction which deviates from the radial and approaches the tangential. The spin velocity in the direction of rotation is thereby increased and the fan is able to do only a decreased amount of work on the fluid. As the deflector is moved farther toward the left in Fig. 3, the component of spin velocity increases and the work done by the fan upon the air is further decreased. Thus, the fan may operate at constant speed, as with an induction motor drive, without the necessity for employing complicated speed control or inefficient throttling devices.

It will be noted that although the deflector 18, as it is moved from the position of Fig. 1 to that of Fig. 3, progressively reduces the area or opening of the throat 20, nevertheless no appreciable throttling occurs. The construction is such that as the deflector is moved to the left of Fig. 3, the spin velocity is so greatly increased that it becomes the predominant factor in determining the work done by the fan and reduces the volume of air to such an extent that it may freely flow through the reduced area of the throat without producing any throttling effect or appreciable loss in efficiency.

The fan described above may be employed for either forced draft or induced draft, or in fact, for any purpose for which centrifugal fans are adapted. For forced draft, the entrance chamber 14 may open directly to the

atmosphere, and for induced draft, the chamber will be connected to the usual ducts.

Having thus described the invention, what is claimed is:

1. A fan comprising an inlet scroll having an eccentric eye and an entrance opening from which the fluid circulates about the scroll to attain a spin component of velocity, and means for varying the direction of the fluid admission to the scroll to vary the magnitude of spin velocity in the scroll prior to admission of fluid to the eye, whereby the output of the fan may be controlled. 70

2. A fan comprising an inlet box including a scroll having an eccentric eye and an entrance chamber connected with the scroll and having an adjustable curved fluid directing wall to direct the fluid to a greater or less extent into the outer peripheral portion of the scroll, and means for adjusting said wall to vary the spin velocity of fluid admitted to the rotor. 80

3. A fan comprising a rotor, an inlet scroll having an eye, an entrance chamber connected with the inlet scroll, the scroll being shaped to cause the fluid to assume a spin velocity prior to the entrance into the eye, and means for varying the spin velocity attained in the scroll including a deflector to vary the direction of delivery of the fluid to the scroll from the entrance chamber. 90

4. A fan comprising an inlet scroll, an entrance chamber therefor having a curved fluid directing wall merging with the scroll, the scroll having an eccentric eye at a distance from the fluid directing wall and nearer the opposite wall of the scroll, a rotor, and a deflector in the entrance chamber adapted to be moved toward the fluid directing wall to direct the fluid entering the scroll to a greater or less extent into the outer periphery of the scroll to increase the spin velocity and thereby to decrease the output of the fan. 100

5. A fan comprising an unobstructed inlet scroll having an eye eccentrically positioned therein, an entrance chamber through which the fluid passes prior to entrance into the scroll, and means exteriorly of the scroll for varying the direction of delivery of air from the chamber to the scroll to control the output of the fan. 110

6. A fan comprising an inlet scroll, an entrance chamber having a curved wall for directing the delivery of air to the scroll, and a curved deflector adjacent said wall and adjustable to form a variable extension thereof to control the direction of the air entering the scroll from the chamber. 120

7. A fan comprising an inlet chamber having an eye therein, an entrance chamber opening into the inlet chamber, the inlet chamber having a curved wall to rotate the fluid in its passage toward the eye, and movable means for varying the opening of the entrance chamber into the inlet chamber to reg- 130

ulate the spin of the air and output of the fan.

8. A fan comprising an inlet chamber having an eye therein, the inlet chamber having a curved wall to rotate the fluid in its passage toward the eye, an entrance chamber having an opening into the inlet chamber for delivering air from the former to the latter and eccentrically of the eye, and means between the entrance and the inlet chamber for determining the extent of eccentricity of such delivery.

9. A fan comprising a rotor, an inlet scroll having an eccentric eye leading to the rotor and an entrance opening wherefrom the fluid circulates about the scroll to attain a spin component of velocity prior to passing through the eye, and adjustable means at the entrance opening for varying the spin velocity attained in the scroll.

10. A fan comprising a rotor, an inlet scroll having an eccentric eye leading to the rotor and an entrance opening wherefrom the fluid circulates about the scroll to attain a spin component of velocity prior to passing through the eye, and adjustable means at the entrance opening for variably directing the fluid toward the outer wall of the scroll.

11. A fan comprising an inlet scroll having an eccentric eye, a rotor, an entrance chamber connected with the scroll and having curved walls to direct fluid toward the outer periphery of the scroll, and an adjustable deflector to vary the extent of fluid direction toward the outer periphery of the scroll to vary the spin velocity assumed by the fluid in passing about the scroll.

12. A fan comprising a rotor, an inlet chamber having a curved outer wall and an eye leading to the rotor, the chamber having an entrance opening to admit the fluid into the chamber tangentially of the eye to cause the fluid to circulate about the chamber and thereby to attain a spin component of velocity prior to passing through the eye, and adjustable means for directing the fluid to a greater or less extent into the outer peripheral portion of the inlet chamber to adjust the spin velocity of the fluid.

13. A fan comprising a rotor, an inlet chamber having a curved outer wall and an eye leading to the rotor, the chamber having an entrance opening to admit the fluid into the chamber tangentially of the eye to cause the fluid to circulate about the chamber and thereby to attain a spin component of velocity prior to passing through the eye, and a deflector for initially directing the fluid to a greater or less extent into the outer peripheral portion of the inlet chamber to vary the spin velocity attained by the fluid in circulating about the chamber.

14. A fan comprising a rotor, an inlet chamber having a curved outer wall and an eye leading to the rotor, the chamber

having an entrance opening to admit the fluid into the chamber tangentially of the eye to cause the fluid to circulate about the chamber and thereby to attain a spin component of velocity prior to passing through the eye, and an adjustable deflector to direct the fluid tangentially into the inlet chamber at varying distances from the rotor axis to vary the magnitude of spin velocity attained by the fluid in circulating about the chamber to the eye.

In testimony whereof I have signed my name to this specification.
